TRUSS

John E. Eddishaw, Atlantic City, N. J.

Application July 17, 1951, Serial No. 237,080

3 Claims. (Cl. 128—107)

1

My invention relates to new and useful improvements in a truss to be worn around the abdomen when the patient has a rupture or hernia of the abdominal viscera.

Still another object of the invention is to provide a truss wherein, besides the usual pad that is placed against the abdomen and an acorn-shaped pressure member, there is provided a metal plate against which bears the pressure member, so that regardless of the position of the body of the wearer, the pressure member will always bear against the plate, and the plate in turn will hold the pad tightly over the hernia or protrusion.

Still another object of the invention is to provide an abdominal truss wherein certain parts may be so adjusted that the pad, plate and pressure member may be adjusted over the hernia, and then these parts buckled in the proper position, so that regardless of the size of the wearer, the pressure will be applied and always applied directly over the hernia.

Still another object of the invention is to provide a truss wherein the encircling band may be made of covered soft rubber so that there is no tendency to rub the body; and wherein the various other parts, to be hereinafter mentioned, may be carefully adjusted to provide a truss that will be comfortable and at the same time very efficient in that the pad against the body will always remain in the same position, regardless of the posture or position of the wearer.

With these and other objects in view the invention consists in certain new and novel arrangements and combinations of parts as will be hereinafter more fully described and pointed out in the claims.

Referring now to the drawings,

Fig. 1 is a side elevation of my improved truss before being attached to the body,

Fig. 2 is a section taken on line 2—2 of Fig. 1,

Fig. 3 is a fragmentary elevation from the opposite side of Fig. 1,

Fig. 4 is an enlarged sectional view taken on line 4—4 of Fig. 1,

Fig. 5 is an enlarged sectional view taken on line 5—5 of Fig. 1,

Fig. 6 is an enlarged sectional view taken through line 6—6 of Fig. 1, and

Fig. 7 is a perspective of the metal plate as shown in Fig. 5.

Referring now more particularly to the several views, and to Figs. 1 and 2 for the moment, there is shown the main strap or belt 1, which is preferably made of fabric; and then there is a layer of soft rubber 2, then the wrapping or cover 3 of fabric, which, as may be seen in Fig. 1, overlaps itself for a portion of the length of the belt as at 4, and the overlap is secured by the snap fasteners 5.

It will be noticed that this outer cover 3 does not overlap at its opposite ends, but is open and flared as at 6 at its one end, and again open near its opposite end as at 7.

By employing the fabric strap 1, and a layer of soft or sponge or foam rubber 2, and the cover 3, the belt or truss will not tend to irritate the wearer, as there is a flexibility and softness due to the rubber insert 2.

Looking at the left-hand end of the belt, in Figs. 1 and 2, there will be seen two pairs of buckles *a* and *b*, which buckles are secured by their respective straps 8 and 9. About centrally of Figs. 1 and 2, there will also be seen a set of straps *c*, which are used to hold the strap member 10 in position, as will be described shortly.

On the right-hand end of the cover 3, where the cover flares as at 7, and on the body side, there is provided a pocket 11 in which there is a pad 11a, which may be made of rubber; and to form this pocket 11 there is a substantially circular piece of fabric 12, which is secured in place by the snap fasteners 13, so that this pad 11a may be removed or changed at any time.

As also may be seen in Figs. 1 and 2, secured to the strap 1, just beyond the pad 11a, are the fastening straps 14 which in turn are secured to the buckles *a* to the left of the view of Fig. 1 to hold the truss tightly in position.

The truss may be placed around the body and the small fastening straps 14 fastened through the buckles *a* at the opposite end to pull the pressure pad 11a directly over the hernia.

Thus, whether the wearer is thin or stout, the truss can be fitted, of course, within certain limitations.

In back of the pocket 11, as may be seen in Fig. 2, there is another pocket 15 formed by having a circular piece of fabric 16, which is fastened in place by the snap fastener 17 to the strap 1; and in this pocket 15 there is placed the metal cup 18, which forms one of the principal parts of the invention.

The plate 18 is preferably rimmed about its periphery as at 19 so that the pressure member, hereafter to be described, can not possibly slip from within the circular contour of the plate 18, regardless of the posture or position of the wearer.

It will be understood that both the pressure pad 11a and the above mentioned plate 18 may vary in size, depending on the size of the wearer; and, of course, if the truss is to be worn by a relatively thin person, the plate may be of a smaller size, whereas if the wearer is obese, stout, or large, a larger plate 18 may be used.

As far as the specification has proceeded, it will be seen that there is a fabric belt 1 with a layer of soft rubber, together with a replaceable pressure pad 11a, and the belt 1 so arranged that

this pressure pad 11a and plate 18 may be fitted directly over the abdominal hernia.

Referring now to what I term the pressure strap member 10, it will be seen that it consists of a fabric strip that is located directly to the rear of the pocket 15, and is provided with the buckles 20' in which fit the aforementioned straps c. To the right-hand end of this fabric strap 10 may be seen the pair of buckles 20, and then there is another strap 21 stitched as at 22 with 10 an eyelet 23 at its inner end, which acts as a guard member, as will be described shortly.

To engage these buckles 20 are the straps 21a seen to the left of Figs. 1 and 2, which straps are in turn held on their inner ends by the buckles b heretofore mentioned.

Thus, the pressure strap 10 is held tightly in position around the body, in addition to the belt portion being held by the straps 14 engaging the buckles a.

Secured to the fabric portion or strap 10 by a stud 24, there is an acorn-shaped pad 25, which is common to a number of forms of trusses, and is inherently rigid, so that when the pressure strap 10 is pulled tightly, it will bear with sufficient pressure against the pocket 15 with its metal plate 18, and the pressure in turn will be transferred to the pressure pad 11a which is directly over the hernia.

Also secured to the stud 24 is the eyelet 26 which eyelet 26 is held by the strap 27 which strap 27 in turn passes under the leg (not shown) and is secured by the buckle 29 on the overlap of the cover of the belt proper, as may be seen in Fig. 1, the buckle being about centrally of the view.

The strap 27 is held near the eyelet 26 by the buckle 29. There is another buckle 30 secured to the strap 1 just adjacent the padded pocket 11 from which a strap 31 is stitched to the leg strap as at 32. The purpose of this is so adjustments may be made as required for the leg strap 27 from the front, and these straps 27 and 31 also tend to hold the pad 11a from slipping.

Thus the truss is held with the pressure pad 11a and the acorn-shaped pressure pad 25 and its plate 18 directly over the hernia in its adjusted position, while the belt proper can not slip up the body or abdomen, regardless of the position or posture of the wearer.

As heretofore mentioned, the eyelet 23 acts as a guard member and is placed over the eyelet 26 on the end of the strap 27 so that there is no possibility of the leg strap 27 becoming disengaged from the heretofore mentioned stud member 24.

It will also be noticed that the strap member 10 is easily replaceable for the purpose that it may be desired to have a longer or shorter strap 27 and a larger or smaller acorn-shaped pad 25 to in turn bear in the pocket 15 and its metal plate 18.

As heretofore mentioned, the truss can be fitted, within certain limits, depending on the size of the wearer; and also a smaller plate and a smaller acorn-shaped pressure member, or vice versa, may quickly be fitted to the truss, depending as aforesaid, on the size of the wearer.

From the foregoing, it will be seen that I have provided a truss that will not irritate the wearer; and wherein, besides the usual pressure members, there is fitted in the pocket a metal plate or disc, so that should the pressure member bear to the right, or bear to the left, it will still be held

tightly against the metal insert, and thus hold the pad directly over the hernia.

Furthermore, the size of the metal plate may be varied; and it is only necessary to unloosen the snap fasteners and put the desired metal plate in place.

Also by having the pressure strap adjustable, as shown, this can be tightened without tightening the main encircling belt or strap.

Finally, all parts are adjustable; and after once adjusted to the wearer, there will be no necessity for changing the same.

I have found the truss one that is very efficient and keeps tight pressure on the protrusion or hernia at all times, regardless of the position of the wearer; and the desired pressure is maintained even if the body belt is not tight.

Many slight changes might be made without departing from the spirit and scope of the invention.

Having thus described my invention, what I claim as new and desire to secure by Letters Patent is:

1. An abdominal truss including an encircling belt formed of fabric, together with a layer of soft rubber, and an outer fabric covering, the outer covering fastened about midway of its length and its opposite ends open, a padded pocket on the body side of the belt, said pocket

30 having a removable outer face, whereby the padding may be renewed; a second pocket having a removable face and a metal rimmed disc located in said last mentioned pocket, an adjustable pressure strap extending over the said last mentioned pocket and having an acorn-shaped pressure member bearing in the last mentioned pocket, the said pressure strap adjustable and removable, and said encircling belt being also adjustable.

2. In an abdominal truss including an adjustable encircling belt, a padded pocket on the body side of the belt, a second pocket directly in back of the first mentioned pocket, both pockets having removable faces; a metal plate located in said last mentioned pocket, a pressure strap extending over said last mentioned pocket, having a pressure member thereon, the pressure member bearing against the pocket containing the metal plate to transfer the pressure to the pressure pad, means for adjusting the pressure strap with respect to the main encircling belt, and a leg strap connected to the pressure strap and to the main encircling belt.

3. In an abdominal truss including an encircling belt, a removable fabric covering, a soft rubber padding substantially coextensive in length with the encircling belt, a pressure pad on the body side of the belt, a metal plate mounted to the rear of said pad, a pressure strap with a pressure member thereon, and adapted to be forced tightly against the said metal plate to transfer the pressure to the pressure pad, and said pressure member exerting pressure at all times on the plate to hold the pad against the hernia of the wearer regardless of the position of the wearer.

JOHN E. EDDISHAW.
